UNITED STATES PATENT OFFICE.

HENRY F. LOEWER, OF ROCHESTER, NEW YORK.

LAST.

No. 872,525.

Specification of Letters Patent.

Patented Dec. 3, 1907.

Application filed February 27, 1905, Serial No. 247,455.

To all whom it may concern:

Be it known that I, HENRY F. LOEWER, a citizen of the United States, and resident of Rochester, in the county of Monroe and 5 State of New York, have invented certain new and useful Improvements in Lasts, of which the following is a specification.

This invention relates to lasts capable of being so reduced in certain of their dimensions as to be capable of easy withdrawal 10 from a shoe which has been fastened tightly upon the last.

In the drawing:—Figure 1 is a longitudinal view of a last embodying this invention with 15 all the parts in place for lasting or finishing a shoe thereon; Fig. 2 is a longitudinal section of the same last showing the parts moved into positions for easy removal of a shoe therefrom; Fig. 3 is a top view of a portion of the 20 instep and toe part of the last; and Fig. 4 is a cross-section on the line 4—4 of Fig. 1.

This last consists of three parts; the toe block 1, the instep block 2, and the heel block 3. In the heel block is fastened, so as to be 25 rotatable therein, a sleeve or thimble 4. The interior of the thimble is of irregular form to fit an irregular shaped key or jack post 5, so that when the key or jack post 5 turns with reference to the last, or vice versa, the parts 30 of the last move automatically, as shown below. Upon the thimble or sleeve 4 is the worm 6, which may be of larger dimensions than the thimble or sleeve so as to rest and be retained in a cavity 7 in the heel 35 block. The worm and thimble may be held in place by a transverse pin 8 upon which the bottom of the worm and thimble rest. A central vertical slot 9 in the heel block holds one end of a lever 10, which is pivoted in the 40 heel block by the pin 11, and has teeth 12 engaging the thread of the worm 6. The lever 10 has a short longitudinal slot 13 near the end opposite to the end having the teeth 12, and between said slot and the pin 11 is a 45 curved slot 14 set transversely to the line connecting the slot 13 and the pin 11 and convex toward the pin 11. In the toe block 1 is a slot 15 to take the lever 10, and a cross pin 16 in the toe block passes through the slot 14, 50 and another cross pin 17 in said toe block passes through the slot 13. The toe block 1 and heel block 3 slide from each other on surfaces 18 diagonal to the bottom of the last and inclining forward from said bottom, so 55 that when the heel block is moved into the position shown in Fig. 2, the last is shortened

to release the shoe, and the last is lengthened to fit the shoe tightly when moved into the position shown in Fig. 1. The movement just described of the toe part with reference 60 to the heel block is produced by turning the last while the jack pin 5 remains stationary, thus rotating the worm 6 by the engagement of the latter with the teeth 12 of the lever 10, tilting the lever upon the pin 11, and moving 65 the toe block 1 forward from the position shown in Fig. 1 to that shown in Fig. 2.

In order to release a shoe from the last with ease and speed it is necessary to reduce the size of the last at the lower part of the instep portion thereof, and for this purpose the present invention embodies an automatically movable instep block 2 which is held to the toe block and is guided so as to move in a proper path to expand the last in one position and to reduce it in another. To the toe block, or to the instep block, is fastened one of the guiding and retaining members, such as the strip or rod 19. In the present embodiment of this invention the said strip or 70 rod 19 is bent up at its middle and is depressed at its ends, which ends are fastened to the instep block 2 by screws 20. Underneath the raised portion of the strip 19 is set the other retaining and guiding member for 75 80 the instep block, which in the present instance consists in a pair of staples 21 spanning the strip 19 and extending into the toe block 1. By these members it is obvious that the instep block 2 may be moved in the 85 direction of its length from the position shown in Fig. 1 to that shown in Fig. 2, and vice versa.

Near the slot 13 in the lever 10 are cut 90 toothed members 23 which engage with corresponding toothed members 24 in a lever 25 pivoted by a pin 26 in the slot 15 and to the toe block 1, so that as the lever 10 oscillates from the position shown in Fig. 1 to that shown in Fig. 2, or vice versa, the lever 25 95 will be oscillated upon the pin 26. The lever 25 has a slot 27 in the end thereof which rests in a slot 28 in the toe block 2. The slot 27 is radial, or substantially radial, with reference to the pin 26 as a center, and a pin 29 100 passes through the slot 27 in the lever 25 and into the toe block.

It will now be seen that upon turning the last upon the jack pin 5, the lever 10 will be rocked from the position shown in Fig. 1 to 110 that shown in Fig. 2, and thereby the lever 25 will be rocked from said position shown in

- Fig. 1 to that shown in Fig. 2, whereby the instep block 2 will be pulled from the position in which it fills the shoe to a position in which it releases the shoe from internal pressure, and at the same time, as before stated, the toe block 1 is lifted and the length of the last is decreased because the heel block and toe part slide upon the diagonal plane surfaces 18.
10. The forward end of the instep block 2 and a meeting portion thereon on the toe block 1 are formed in corresponding angular surfaces 22, Fig. 3, whereby the instep block is guided in accurate position on the toe block.
15. What I claim is:
1. In a last, a heel block, a toe block, a connection for connecting the two parts together, an instep block sliding upon said toe block, a connection between said toe block and said instep block, and means for sliding said instep block by simultaneous movement of said connections.
  2. In a last, a heel block, a toe block, a connection for connecting the two parts slidably together, an instep block sliding upon said toe block, and means for sliding said instep block by said connection.
  3. In a last, a heel block, a toe block, a connection for connecting the two parts together, an instep block sliding upon said toe block, means for sliding said instep block by said connection, and a rotary thimble in said heel block for actuating said connection.
  4. In a last, a heel block, a toe block, a connection for connecting the two parts together, a rotary worm thimble in said heel block engaging said connection for actuating the latter, an instep block sliding upon said toe block, and means for sliding said instep block by said connection.
  5. In a last, a heel block, a toe block, a lever pivoted to the heel block and extending into and attached to the toe block, a rotary thimble in said heel block engaging said lever for actuating the same, an instep block sliding upon the said toe block, and means for sliding said instep block by movement of said lever.
  6. In a last, a heel block, a toe block, a connection for connecting the two parts together, an instep block sliding upon said toe block, and a part geared to said connection and connected to said instep block for sliding the latter by movement of said connection.
  55. 7. In a last, a heel block, a toe block, a connection for connecting the two parts slidably together, an instep block sliding upon said toe block, and a part geared to said connection and connected to said instep block for sliding the latter by movement of said connection.
  60. 8. In a last, a heel block, a toe block, a connection for connecting the two parts together, an instep block sliding upon said toe block, a part geared to said connection and

connected to said instep block for sliding the latter by movement of said connection, and a rotary thimble in said heel block for actuating said connection.

9. In a last, a heel block, a toe block, a connection for connecting the two parts together, an instep block sliding upon said toe block, a part geared to said connection and connected to said instep block for sliding the latter by movement of said connection, and a rotary worm thimble in said heel block engaging said connection for actuating the latter.

10. In a last, a heel block, a toe block, a lever pivoted to the heel block and extending into and attached to the toe block, a rotary thimble in said heel block engaging said lever for actuating the same, an instep block sliding upon the said toe block, and a part geared to said connection and connected to said instep block for sliding said instep block by movement of said connection.

11. In a last, a heel block, a toe block, a connection for connecting the two parts together, an instep block sliding upon said toe block, and a lever pivoted to said toe block and engaging said instep block and said connection and actuated by the connection for sliding said instep block back and forth.

12. In a last, a heel block, a toe block, a connection for connecting the two parts together, an instep block sliding upon said toe block, a part geared to said connection and connected to said instep block for sliding the latter by movement of said connection, and a lever pivoted to said toe block and engaging said instep block and said connection and actuated by the connection for sliding said instep block back and forth.

13. In a last, a heel block, a toe block, a connection for connecting the two parts slidably together, an instep block sliding upon said toe block, a part geared to said connection and connected to said instep block for sliding the latter by movement of said connection, and a lever pivoted to said toe block and engaging said instep block and said connection and actuated by the connection for sliding said instep block back and forth.

14. In a last, a heel block, a toe block, a connection for connecting the two parts together, an instep block sliding upon said toe block, a rotary thimble in said instep block for actuating said connection, and a lever pivoted to said toe block and engaging said instep block and said connection and actuated by the connection for sliding said instep block back and forth.

15. In a last, a heel block, a toe block, a connection for connecting the two parts together, an instep block sliding upon said toe block, a rotary worm thimble in said heel block engaging said connection for actuating the latter, and a lever pivoted to said toe

block and engaging said instep block and said connection and actuated by the connection for sliding said instep block back and forth.

5 16. In a last, a heel block, a toe block, a lever pivoted to the heel block and extending into and attached to the toe block, a rotary thimble in said heel block engaging said lever for actuating the same; an instep block

sliding upon the said toe block, and a lever 10 pivoted to said toe block and engaging said instep block and said first-mentioned lever and actuated by the first-mentioned lever for sliding said instep block back and forth.
